CLAIM

The ornamental design for a combined cosmetic applicator and cap, as shown and described.

DESCRIPTION

FIG. 1 is a perspective view of a combined cosmetic applicator with cap showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view of the applicator with its cap removed, for clarity of illustration;

FIG. 8 is a front elevational view thereof;

FIG. 9 is a rear elevational view thereof; and

FIG. 10 is a top plan view thereof.
